US00D597356S

(12) **United States Design Patent**
Storz

(10) **Patent No.:** **US D597,356 S**
(45) **Date of Patent:** **** Aug. 4, 2009**

(54) **DISPENSER**

(75) Inventor: **Achim Storz**, Zell am See (AT)

(73) Assignee: **Hans Georg Hagleitner** (AT)

(**) Term: **14 Years**

(21) Appl. No.: **29/287,105**

(22) Filed: **Jun. 27, 2007**

(30) **Foreign Application Priority Data**

Jan. 9, 2007 (EM) 000648779

(51) **LOC (9) Cl.** **06-04**

(52) **U.S. Cl.** **D6/545**

(58) **Field of Classification Search** D9/730;

D6/542-545; 222/105, 173, 180, 181.1,
222/181.2, 181.3; 221/208, 282, 283

See application file for complete search history.
